UNITED STATES PATENT OFFICE

159,688

COMBINED BED, CHAIR, AND EXERCISER

Edward E. Socol, Chicago, Ill.

Application May 31, 1949, Serial No. 2,973

Term of patent 14 years

(Cl. D5—4)

To all whom it may concern:

Be it known that I, Edward E. Socol, a citizen of the United States, residing at Chicago, in the county of Cook and State of Illinois, have invented a new, original, and ornamental Design for a Combined Bed, Chair and Exerciser, of which the following is a specification, reference being had to the accompanying drawing, forming part thereof.

I claim:

The ornamental design for a combined bed, chair and exerciser, as shown.

EDWARD E. SOCOL.
